UNITED STATES PATENT OFFICE.

G. RALSTON AYRES, OF PHILADELPHIA, PENNSYLVANIA, ASSIGNOR TO HIMSELF, WILLIAM MONTGOMERY AYRES, AND LOUIS H. AYRES, ALL OF SAME PLACE.

DESIGN FOR A HORSE-SHEET.

SPECIFICATION forming part of Design No. 17,864, dated November 8, 1887.

Application filed April 23, 1887. Serial No. 235,944. Term of patent 14 years.

To all whom it may concern:

Be it known that I, G. RALSTON AYRES, a citizen of the United States, and a resident of Philadelphia, Pennsylvania, have invented a new and original Design for a Horse-Sheet, of which the following is a specification.

My design is fully shown in the accompanying drawings, in which—

Figure 1 is a side view of a horse-sheet embodying the design, and Fig. 2 an enlarged view showing the pattern more clearly.

The sheet has the curved back-border *a*, a curved neck border *b*, front and rear borders, *d* and *f*, and bottom border, *g*, and the body of the sheet has alternating transverse stripes *m*' and *n*' and longitudinal stripes *m* and *n*, forming a plaid. Each of the stripes *m*' and *n*' is composed of a series of smaller stripes, *w*, those of the stripes *n*' being of uniform width, while those of the stripes *m*' are alternately wide and narrow, and each of these stripes *w* is composed of a succession of transverse bars of a step-like character, as shown in Fig. 2, this being essential to the design.

I claim—

1. The within-described design for a pattern for horse-sheets, said design consisting of

stripes *m* *m*' and *n* *n*', crossing each other to form a plaid, the stripes *m* *m*' consisting of a series of alternating wide and narrow stripes *w*, and the stripes *n* *n*' consisting wholly of narrow stripes *w*, each of said stripes *w* being composed of transverse bars of a step-like character, all substantially as shown and described.

2. The within-described design for a horse-sheet, said design consisting of curved back and neck borders, the front, rear, and bottom borders, and the body having a pattern consisting of stripes *m* *m*' and *n* *n*', crossing each other to form a plaid, the stripes *m* *m*' consisting of alternate wide and narrow stripes *w*, and the stripes *n* *n*' consisting wholly of narrow stripes *w*, each of said stripes *w* being composed of transverse bars of a step-like character, all substantially as shown and described.

In testimony whereof I have signed my name to this specification in the presence of two subscribing witnesses.

G. RALSTON AYRES.
